UNITED STATES PATENT OFFICE.

JACOB H. KRAILING, OF EAST HAVEN, CONNECTICUT.

DESIGN FOR A BOX COVERING.

Application filed October 22, 1925. Serial No. 15,221. Term of patent 14 years.

To all whom it may concern:

Be it known that I, JACOB H. KRAILING, a citizen of the United States, and resident of East Haven, in the county of New Haven and State of Connecticut, have invented a Box Covering, of which the following is a accompanying drawing, forming part hereof.

The drawing is a development view of the top, sides and ends of a box with the design applied thereto.

I claim:

The ornamental design for a box covering, as shown.

In testimony whereof I have hereunto set specification, reference being had to the my hand.

JACOB H. KRAILING.
